UNITED STATES PATENT OFFICE.

CLAUDE WILLIAM ATKINSON, OF GREAT MISSENDEN, ENGLAND.

PIANO-PLAYING MECHANISM AND THE LIKE.

1,043,792.

Specification of Letters Patent.

Patented Nov. 12, 1912.

Application filed January 14, 1910. Serial No. 538,013.

To all whom it may concern:

Be it known that I, CLAUDE WILLIAM ATKINSON, a subject of the King of Great Britain and Ireland, residing at Great Missenden, in the county of Bucks, England, have invented new and useful Improvements in and Relating to Piano-Playing Mechanism and the Like, of which the following is a specification.

10 This invention relates to improvements in piano playing mechanism and has for its object means by which the operator can vary the strength of the notes as a whole and can accent a particular note at will.

15 In mechanical piano players as at present made the strength of the blows sounding the notes is controlled by regulating the rapidity with which air is withdrawn from the power pneumatics which operate the 20 sound producing devices of the piano, or in other words by regulating the pressure which is causing a flow of air from the power pneumatics. This control is effected by placing a valve system between the pipe leading to the vacuum chest from the source 25 of power.

The difficulty which is experienced with the present form of control valve is that the amount by which the valve has to be opened 30 to obtain a certain strength of blow, depends on the number of notes to be struck simultaneously. That is to say, the valve must be opened wider if a chord is to be struck than if a single note is to be sounded.

35 As a result it is only possible to utilize these control valves for emphasizing notes or chords and the general effect of loudness or softness must be obtained by varying the pressure of the vacuum or by means of the 40 pedaling and this makes it difficult for instance to play loudly on the treble while the bass is subdued.

Now according to my invention I employ two valves for the purposes of control, a 45 valve of the flap form or shutter form, which is only used for accenting notes or passages, which at the will of the operator is opened wide or shut more or less completely, and a second valve which is con-

trolled by a spring, means being provided 50 for varying the strength of this spring by the operator from the key board. These two valves are placed on a wall or division located in the passage leading from the source of power to the vacuum chest, and 55 completely separating the two sides of this passage, to enable the difference of pressure between one side and the other to be varied at the will of the operator.

The spring controlled valve will produce 60 a definite difference of pressure from one side of it to the other when the controlling spring is adjusted to a definite amount, and whether one note or a chord is sounded the 65 difference of pressure is the same, the opening of the valve adjusting itself to the amount of air passing by it. This valve regulates the strength of the notes as a whole, and the spring control of this valve may be so varied that the notes are only 70 sounded softly while a considerable pressure is being maintained by pedaling, and then the moment the hand operated valve is opened the pressure on the power pneumatics will be instantly raised and the note, 75 chord, or passage accented.

In order that my invention may be the better understood I will now describe the same in relation to the accompanying drawings, reference being had to the letters and 80 figures marked thereon.

Like letters refer to like parts in the various figures.

Figure 1 is a sectional elevation of the controlling valves. Fig. 2 is a plan of same. 85 Fig. 3 is diagrammatic representation of the regulating valve applied to a piano player in which the power pneumatics are surrounded by the atmosphere and their interior connected with exhaust when operated similar to the arrangement used in the well known Pianola piano player.

A plate *a* separates the space of high pressure from that of low pressure, the higher pressure being above the upper surface of the plate in Fig. 1. Upon this plate is mounted a second plate *b* having a facing *c* of leather, felt or similar material and

through this plate and facing, holes *d* and *e* are cut to allow air to pass from the higher to the lower pressure, that is in a downward direction through the plate. These holes are 5 closed by valves *f* and *j*.

The valve *f* of circular or other suitable form is supported on a stem *g* passing through a guiding hole in the plate *b* and is suspended from a spring *h* attached to the 10 rod or string *i* which is led up to an operating lever *n* mounted on the control board *o* of the piano player.

Now when the pressure on the top side of the plate *a* is higher than that on the 15 lower side a pressure is exerted in a downward direction on the valve *f* tending to open the valve and this pressure is balanced by the spring *h*. When the difference in pressures between the two sides of the plate 20 *a* exceeds the pressure which just balances the tension on the spring the valve *f* will open and will allow air to pass from the top side of the plate *a* to the bottom, and the source of pressure is then put in communication with the power pneumatics.

The difference of pressure required to 25 open the valve *f* can be regulated by movement of the lever *n* on the control board *o* of the piano player.

30 The amount by which the valve *f* opens depends on the number of power pneumatics in operation at any moment, that is on the amount of air which is required to pass by the valve to keep the difference in pressure between the upper and under surfaces equal to the tension on the spring. Thus whether 35 a single note or a chord is being sounded the pressure on the power pneumatics is the same and the note or chord is sounded with an equal force. I use this valve for controlling the loudness of the music as a whole or in controlling the accompaniment. For emphasizing single notes, chords or passages I 40 use the valve *j* and by suddenly opening this

45 I can instantaneously decrease the difference in pressure between the spaces above and below the plate *a* and therefore increase the tension on the power pneumatic and I thus cause the notes then being operated to be 50 sounded louder. In the drawing I have shown a shutter valve *j* mounted on a spindle *l* attached to the plate *b* and capable of being caused to revolve about the spindle by means of a cord *m* wrapped around the 55 stem *k* of the valve *j* and attached to a lever *p* on the control board *o* of the instrument. The valve is returned to its closed position by the action of the spring *m'*. By the combination of these two valves I can effectively 60 control both the accompaniment and the melody in a piece of music.

Although I have shown a shutter valve *j* and a mushroom valve *f* I do not limit myself to these forms of valves, and I may if I

like use hinged flap valves or sliding valves 65 of any of the usual forms.

The operation of my valves is as follows:—If a pressure equal to say three inches of water is required to strike a soft or piano note, then I may set the spring *h* 70 on my valve *f* so that the valve by moving the lever *n* opens when there is a difference of pressure between the upper and lower surfaces equal to three inches. I then pedal till the pressure in the vacuum reservoir is 75 say six inches. The pressure on the pneumatics will then be three inches that is the difference between the pressure in the reservoir and the difference of pressure between the two sides of the spring controlled 80 valve, and this will be the case whatever number of notes is being sounded simultaneously. I can now emphasize or pick out any notes which I wish to do by opening the shutter valve at the moment the perforations 85 in the music sheet corresponding to the note to be emphasized is approaching the hole in the tracker board. If I open the shutter valve wide there will be no appreciable difference of pressure in passing by this valve 90 and the pressure on the power pneumatics will be instantaneously raised to six inches, and I may obtain any intermediate pressure between the three inches which is given by the spring controlled valve and the full six 95 inches by opening the shutter valve by a suitable amount. Similar results can be obtained by the adjustment of the spring on the spring controlled valve to any other pressure. It will be seen that these results 100 cannot be obtained by the use of pneumatically controlled regulating valves since their action depends on the pressure in the vacuum reservoir, instead of being independent of it as is the case in my invention. It will 105 be understood that I may use more than one such combinations of valves to control independent sections of notes.

Having now particularly described my invention, what I desire to secure by Letters 110 Patent is:—

In piano playing mechanism an air control device for regulating the strength of a series of notes and accenting a particular note or notes at will consisting of in combination a wall or division disposed in the passage between the vacuum chest and the source of power, an orifice in said wall or division, a valve seat around said orifice, an automatic control valve on said seat located 115 on the side of the said wall or division adjacent to the source of power, said automatic valve being movable toward and from its seat, a spring connected to said valve, hand operated means on the control board of the 120 piano playing mechanism connected to said spring, a second orifice in said wall or division, a second valve coacting with said ori-

fice, operating means for working said valve, a second hand operated means on the control board of the piano playing mechanism and connecting means from said second hand operated means to said second valve, substantially as described.

In testimony whereof I have signed my

name to this specification in the presence of two subscribing witnesses.

CLAUDE WILLIAM ATKINSON.
